UNITED STATES PATENT OFFICE.

JESSIE PIERPOINT, OF YONKERS, NEW YORK.

BALL-BEARING RAIL.

1,404,641.

Specification of Letters Patent. Patented Jan. 24, 1922.

Application filed October 8, 1921. Serial No. 506,335.

To all whom it may concern:

Be it known that I, JESSIE PIERPOINT, a citizen of the United States, residing at Yonkers, in the county of Westchester, State 5 of New York, have invented certain new and useful Improvements in Ball-Bearing Rails; and I do hereby declare the following to be a full, clear, and exact description of the invention, such as will enable others 10 skilled in the art to which it appertains to make and use the same.

This invention relates to new and useful improvements in railway appliances and particularly to attachments for railway 15 rails.

One object of the invention is to provide an antifriction means for the rails of a curve against which the wheels of a train are adapted to bear to relieve the wheels 20 and rails of wear and strain, the attachment being so constructed and arranged that it may be readily applied to the rails now in use without any modifications to the rails, or displacements thereof.

Another object is to provide a device of 25 this character which is simple in construction, is readily applicable to the ordinary railway curves, and which can be manufactured at a comparatively low cost.

Other objects and advantages will be apparent from the following description when taken in connection with the accompanying 30 drawing.

In the drawing:

Figure 1 is a top plan view of a railway 35 curve showing the invention applied thereto.

Figure 2 is a side elevation of the same.

Figure 3 is an enlarged vertical trans- 40 verse sectional view on the line 3—3 of Figure 1.

Referring particularly to the accompany- 45 ing drawing, there are shown the inner and outer rails 10 and 11, of the curve of a rail- way, in connection with which the present invention is adapted for use. Each of the rails includes the tread 12, web 13, and base flanges 14. The rails 10 and 11 are secured to the usual ties 15.

Disposed on the end portions of the ties, 50 outwardly of the outer rail 10, is a curved rail 16, including a base flange 17, a vertical web 18, and an upper outwardly extending portion 19. The lower end of the web has formed thereon the downwardly and in-

wardly extending lugs 20 which engage beneath the base of the rail 10, while the base of the rail 16 rests on the upper faces of the tie ends. The web 18, of the rail 16 is disposed in close proximity to the web of the rail 10, as clearly seen in the section 60 Figure 3, with the upper face thereof disposed beneath the tread of the rail 10. The inner portion of the member 19 is formed with a longitudinally extending groove or race 21 in which are located the series of 65 bearing balls 22, the groove and balls being located above the tread face of the rail 10 to be engaged by the side face of the car wheel 23, as the car rounds the curve. Between the member 19 and the base 17, are 70 formed the bracing webs 27 which support the member 19 against the outward and downward pressure of the wheels against the balls and the member 19. The rail 16 is secured to the ties by means of the spikes 75 25, which extend through the entire length of the curved portion of the rail 10. The upper and lower walls of the groove or race 21 extend inwardly beyond the centers of the balls 22 whereby the balls are secured 80 within the groove, while being permitted to rotate freely therein, as the wheel engages therewith.

The peculiar construction and arrange- 85 ment of the rail 16, with respect to the rail 10 and the ties 15, effectively prevent move- ment of the rail 16 in any direction, while rendering it unnecessary to modify the construction of the rail 10.

What is claimed is:

An attachment for a railway curve comprising a curved rail having a base flange formed with downwardly inclined lugs, a vertical web, and a longitudinally grooved upper portion, and bearing balls disposed in the 95 grooved portion, the said grooved portion being formed to lie above the tread portion of a railway rail and to have its lower portion underlie the said tread portion, with bracing webs extending between the base 100 flange and the upper grooved portion.

In testimony whereof, I affix my signature, in the presence of two witnesses.

JESSIE PIERPOINT.
